(57) **CLAIM**

The ornamental design for a charging station for electric vehicle, as shown and described.

DESCRIPTION

FIG. 1 is a front, left side perspective view of the charging station for electric vehicle of the present invention;
 FIG. 2 is a front, right side perspective view thereof;
 FIG. 3 is a rear, right side perspective view thereof;
 FIG. 4 is a rear, left side perspective view thereof;
 FIG. 5 is a front view thereof;
 FIG. 6 is a rear view thereof;
 FIG. 7 is a right side view thereof;
 FIG. 8 is a left side view thereof;
 FIG. 9 is a top view thereof; and,
 FIG. 10 is a bottom view thereof.
